UNITED STATES PATENT OFFICE.

WASHINGTON I. SCHRYVER, OF PROPHETSTOWN, ILLINOIS.

WAGON-JACK.

SPECIFICATION forming part of Letters Patent No. 329,089, dated October 27, 1885.

Application filed September 14, 1885. Serial No. 177,079. (No model.)

To all whom it may concern:

Be it known that I, WASHINGTON I. SCHRYVER, a citizen of the United States, residing at Prophetstown, in the county of Whiteside 5 and State of Illinois, have invented a new and useful Improvement in Wagon-Jacks, of which the following is a specification, reference being had to the accompanying drawings.

My invention has relation to improvements 10 in lifting-jacks; and the novelty consists in the peculiar construction, combination, arrangement, and adaptation of the various parts for service, substantially as hereinafter fully set forth, and specifically pointed out in the 15 claims.

The object of my invention is to provide a jack especially adapted for elevating the axle of wagons or other like vehicles, which shall be capable of adjustment to elevate the axle 20 to any desired elevation with a minimum of power and exertion on the part of the attendant, which shall be very simple, strong, and durable in construction, thoroughly effective and easy in operation, and comparatively 25 cheap of manufacture.

I have shown an embodiment of my invention in the accompanying drawings, in which—Figure 1 is a perspective view of my improved lifting-jack. Fig. 2 is a side elevation of the 30 operating-lever depressed and the axle-supporting dog elevated. Fig. 3 is a front elevation. Fig. 4 is a horizontal cross-section through the holding-dog on the line $x-x$ of Fig. 2.

Like letters of reference indicate corresponding parts in all the figures of the drawings, referring to which, A designates my improved lifting-jack, comprising a base, B, a standard, C, secured upon the base, an operating-lever 45 D, pivoted in the upper end of the standard, a rack-bar, E, pivotally connected to the operating-lever and the standard, a holding-dog F, mounted or secured upon the rack-bar and free to slide thereon, and a bail, G, pivotally connected to the standard and adapted 50 to engage one of a series of notches on the operating-lever, the peculiar construction and arrangement of the several parts of which I will now proceed to describe more fully.

The standard C comprises two parallel bars 55 or uprights, C', which are bent outwardly from

each other at their lower ends, as at c, and bolted or otherwise suitably secured upon the base B. A brace, C', extends transversely across the plane of the lower ends of the 55 standard, between the parallel bars of which it is fitted, and is bolted thereto, as at c', and at their ends to the base, as at c'.

The operating-lever D is preferably curved and of the form shown, the rear end thereof 60 having a handle, d, and a series of notches, d', in the upper edge, beyond the handle, while near its front end said lever is pivoted between the upper ends of the parallel bars of the standard C, as at d', to leave a projection or arm, d', on the opposite side of the said standard, to which is pivoted the rack-bar E, which comprises two parallel bars, E', arranged on opposite sides of the lever and pivoted thereto, as described, by a cross-bolt, e. The lower ends of the parallel uprights of the rack-bar are pivoted, as at e', to a link or toggle lever, E', which in turn is pivoted, as at e', between the parallel uprights of the standard C, as clearly shown.

The supporting-dog F is provided with a shank, f, which passes between the parallel rack-bars, and at its rear end it is provided with laterally-projecting lugs f', which bear on the rear faces of the rack-bar. A tooth 80 or projection, f', extends below the body of the dog, and is adapted to engage one of the series of notches or teeth in the rack-bars. The dog is free to slide up and down on the rack-bars, the lateral lugs of the shank thereof bearing loosely against the rack-bars, to permit the dog to be pulled outwardly, so that the tooth f' thereof can be disengaged from the notch which it fits, and the dog be moved to the desired position on the rack-bars, as 85 will be verily understood.

The rear end of the link E' has an eye, g, secured thereto or formed therewith, and to this eye g is pivotally connected the lower end of the bail G, the upper or front end of which 95 passes over the operating-lever, and is adapted to engage one of a series of notches, d', therein to hold the lever from downward movement under the weight of the vehicle and axle, as is obvious.

From the foregoing description, taken in connection with the drawings, it will be observed

that the holding-dog F can be adjusted to any desired position on the rack-bars independently of the operating-lever, and in practice the device is placed in proper position beneath the 5 axle of a vehicle, the dog adjusted so that it will engage, or nearly so, the under face of the axle, and the outer end of the lever depressed, thus elevating the dog and rack-bars, and carrying with them the vehicle-axle. The bail G 10 is then engaged with one of the notches in the lever to prevent the outer end thereof being elevated under the weight of the vehicle.

It will be observed that the device can be quickly and readily adjusted beneath and removed from the vehicle-axle, that it requires but a minimum expenditure of power or exertion on the part of the attendant to operate the device, that it is very simple, strong, and durable in construction, and can be manufactured 15 and sold comparatively cheap.

The front projecting end or arm, d^3 , of the lever and the link E^2 are of the same length, and when the lever is operated they move in the same planes, thus keeping the rack-bars parallel with and at an equal distance at their upper and lower ends from the standard C, and the supporting adjustable dog F, being arranged at a right angle to and projecting from the outer vertical face of said rack-bars, is consequently 25 maintained at all times in a horizontal position, and to these particular arrangements of parts I attach especial importance.

Various slight changes in the form and proportions of parts can be made without departing 30 from the spirit of my invention.

Having thus fully described my invention,

what I claim as new, and desire to secure by Letters Patent, is—

1. In a lifting-jack, the combination of a standard, a lever pivoted thereto, parallel 40 rack-bars pivoted to the lever, a link pivotally connected to the standard and the rack-bars, a bail pivoted to the link and fitting over the lever, and a vertically-adjustable dog mounted on the rack-bars, substantially as described. 45

2. In a lifting-jack, and in combination with the standard and operating - lever' thereof, rack-bars pivotally connected to the lever and standard, and an adjustable dog mounted on 50 the rack-bars and having a shank fitting between the same, and a tooth engaging one of a series of teeth thereof, substantially as described.

3. In a lifting-jack, the combination of the 55 following elements, namely: a base, B, a standard, C, mounted thereon, braces C^2 connected to the base and standard, a lever, D, pivoted to the standard and having teeth d^3 , parallel rack-bars E' ,pivoted to the lever, a link, E^2 , pivoted 60 to the standard and the rack-bars, an adjustable dog, F, having a shank, f, provided with lateral lugs f' , and a downwardly-projecting tooth, f^2 , and a bail, G, pivoted to an eye of the link E^2 , substantially as described. 65

In testimony that I claim the foregoing as my own I have hereto affixed my signature in presence of two witnesses.

WASHINGTON I. SCHRYVER.
